COMBINED ELECTRIC PROTECTION AND
WARP STOP FOR LOOMSFrederick W. Paul, Worcester, Mass., assignor to
Crompton & Knowles Loom Works, Worcester,
Mass., a corporation of Massachusetts

Application April 3, 1950, Serial No. 153,644

6 Claims. (Cl. 139—341)

1

This invention relates to improvements in a loom having electric protection and an electric warp stop motion and it is the general object of the invention to provide protection and warp stop interconnected electric circuits controlling a common knock-off mechanism and acting to stop the loom if the shuttle is running behind schedule or a drop wire has fallen due to a broken warp thread.

There has recently been developed a form of electric protection for looms wherein the shuttle if running properly gives indication of timely arrival at a given point along the lay between the shuttle boxes and in doing so permits the loom to continue running. If, however, the shuttle is slow in reaching the given point and there is likelihood that the shuttle can be trapped in the warp shed mechanism acts to stop the loom promptly. Because of the importance of protection in a loom it is desirable that conditions be set normally so that the loom will stop unless the normal setting is canceled by timely arrival of the shuttle at the aforesaid given point along the lay, and in order to accomplish this result a force transmitted under control of the solenoid may be normally positioned in the path of a regularly rocking knock-off lever to be moved out of the path if the shuttle is on time, but be left in the path if the shuttle is late.

Electric warp stop motions generally employ some form of knock-off mechanism including a regularly rocking actuator or the like, which upon occurrence of a warp fault cooperates with an electromagnetically controlled force transmitter to effect loom stoppage. When the electric protection of the type mentioned is combined with electric warp stop means and the shuttle is running properly the condition can arise in which the solenoid would be energized to move the force transmitter out of the path of the actuator at the time when a broken warp thread requires that the transmitter be left in the path.

It is an important object of the present invention to locate a switch in the protector circuit normally closed so that the shuttle can energize the solenoid, but if a warp fault occurs the switch is opened so that although the shuttle is on time and closes its switch the solenoid cannot be energized and the force transmitter will remain in the path of the actuator to effect loom stoppage.

With these and other objects in view which will appear as the description proceeds, the invention resides in the combination and arrangement of parts hereinafter described and set forth.

2

In the accompanying drawings, wherein a convenient embodiment of the invention is set forth,

Fig. 1 is a side elevation of part of a loom having the invention applied thereto, and

Fig. 2 is a diagram of the electric circuits used with the invention.

Referring particularly to Fig. 1, the loom frame 1 supports top and bottom shafts 2 and 3 which are generally geared together so that the top shaft rotates once for each pick or beat of the loom and the bottom shaft rotates every other pick of the loom. The system of warp threads designate generally at W is divided into top and bottom warp sheds W1 and W2 by harness mechanism indicated generally at 4 and 5.

Associated with the system of warp threads is a warp stop motion designated generally at 6 including several banks, four banks being shown in Fig. 1. The drop wires 7 are individually supported by the warp threads and whenever a warp thread breaks or becomes unduly slack the associated drop wire falls and in doing so electrically connects the electrodes of a contact bar. In Fig. 2 one of these contact bars 8 is indicated as having an outer and generally grounded electrode 9 and an inner insulated electrode 10. The warp stop motion may be of the type shown in Payne Patent No. 1,852,217.

The lay 11 is reciprocated by the top shaft through connectors one of which is indicated at 12 and rocks back and forth in a more or less horizontal direction, completing a reciprocation each pick or beat of the loom. During the backward stroke of the lay the shuttle S will generally be picked and pass through the warp shed and ordinarily emerge from the shed during the ensuing forward stroke of the lay. If for any reason the shuttle fails to leave the warp shed it is necessary to stop the loom promptly in order to prevent a warp smash.

Operation of the loom is controlled by shipper mechanism designated generally at 15 and including a handle 16 having a downwardly extending arm 17 connected to a rod 18 leading to a knock-off mechanism designated generally at 19. A lever 20 connected to the rear end of rod 18 is pivoted as at 21 to the mechanism 19 and has pivoted thereto a force transmitting element or link 22 under control of a normally deenergized electromagnetic device, such as a solenoid 23. The solenoid is normally deenergized to permit link 22 to be down in its normal position shown in full lines in Fig. 2, but when the solenoid is energized it raises the link to the non-stopping position shown in full lines, Fig. 1, and dotted

lines, Fig. 2. When in the down or stopping position link will rest on a stop 24.

A regularly moving knock-off lever 25 pivoted as at 26 to the mechanism 15 is rocked in one-pick time by a cam 27 secured to the bottom shaft 3 and having opposite lobes 28. Actuator or knock-off lever 25 is given a working stroke in a counter-clockwise direction as viewed in Fig. 1 by cam 27 each pick of the loom, preferably when the lay is moving forwardly. If the link 22 is in non-stopping position out of the path of the lever 25 the loom will continue to run, but if the link is in stopping position rod 18 will be pushed forwardly to shift the shipper mechanism 15 from the running to the stopping position and mechanism not shown herein but well understood thereupon operates to effect prompt loom stoppage. The loom stopping mechanism including lever 25, link 22, and rod 18 may be similar to that shown in Payne Patent No. 1,873,465, except that in the patent the link is normally out of the path of the knock-off lever.

The electric protector mechanism includes a plunger or rod 30 slidable vertically in the lay 11 and normally projecting upwardly a slight distance into the path of the shuttle S. This plunger is located at some point along the lay between its ends to be depressed by the shuttle while the latter is in flight and preferably though not necessarily while the shuttle is still in the warp shed. A normally open shuttle operated switch SS is mounted on the lay and has a blade 31 for engagement with a contact 32, see Fig. 2. The blade is controlled by a small lever 33 on the lay normally in raised position but pushed down as the shuttle passes over and depresses the plunger 30, and when pushed down lever 33 causes blade 31 to engage contact 32 and thus close the shuttle switch SS.

When a holdover device is desired for the switch SS the same may be provided by a locking lever 35 pivoted as at 36 to the lay and having the lower end 37 for cooperation with a stationary stop 38. The lever 35 slips over and hooks the lever 33 in down position when plunger 30 is depressed by the shuttle. This operation occurs while the lay is still a considerable distance from its front center position and as the lay approaches front center the stop 38 engages lever 35 to rock it in a counter-clockwise direction as viewed in Fig. 1 to release the lever 33, whereupon the latter and the plunger are restored to their normal raised position preparatory to another operation by the shuttle on the next pick of the loom.

The plunger 30, switch SS and holding lever 35 form part of the subject matter of copending application Serial No. 134,001, filed by Moss, December 20, 1949, and are not specifically claimed herein. The present invention is not limited to the form of switch SS shown, and it will be sufficient for the purposes of the invention if the shuttle when passing a given point along the lay operates to close a switch or otherwise closes the loom protection circuit to be described hereinafter.

In carrying the present invention into effect provision is made to control the link 22 from both the warp stop motion and the electric protection. Normally, switch SS will be open and link 22 will be in the path of lever 25. When the shuttle closes switch SS the following normally open loom protection circuit will be closed: transformer T, wire 40, switch blade 41 of warp stop controlled switch WS, contact 42, wire 43, blade 31 (dotted lines, Fig. 2), contact 32, wire 44, solenoid 23, and wire 45 back to the transformer.

If this normally open circuit is closed on time by depression of plunger 30 by the shuttle, link 22 will be lifted (dotted lines, Fig. 2) out of the path of lever 25 before the latter has its working stroke and the loom will continue to run. If the shuttle is running late, however, link 22 will remain in the path of lever 25 when the latter has its working stroke and link 22 will be moved to the left, Fig. 2, to move the rod 18 forwardly to effect prompt loom stoppage, as already described.

When a drop wire falls it closes the following normally open warp stop circuit: transformer T, wires 40 and 50, contact bar 6, wire 51, electro-magnet 52, wire 53, and wire 45 back to the transformer. When this circuit is closed the electro-magnet 52 will be energized and blade 41, which is an armature of the electro-magnet, will be drawn out of engagement with contact 42. When the protector circuit is thus broken the solenoid 23 will remain deenergized even though the shuttle should be on time and close switch SS. Under these conditions the solenoid 23 will not be able to lift link 22 and the latter, being in the path of the lever 25, will be moved to effect loom stoppage.

If the shuttle should be running slow and a drop wire should fall shortly after lever 25 engages link 22 the protector circuit will be open at the warp stop switch WS by movement of blade 41 and will remain open until the warp fault is corrected. Merely placing the shuttle in its box and resuming weaving even if resulting in closure of switch SS, will not cancel the warp stop indication, and when lever 25 has its next working stroke the loom will again be stopped. If the warp fault should occur just before the shuttle reaches plunger 30 switch WS will open the protector circuit and timely depression of plunger 30 by the shuttle cannot have the effect of energizing solenoid 23 and the loom will be stopped.

From the foregoing it will be seen that the invention sets forth simple means by which a single solenoid can be utilized with both the electric protection and warp stop circuits despite the fact that the protection circuit requires energization of the solenoid 23 while operation of the warp stop circuit requires that the solenoid be deenergized. This result is accomplished by having a warp stop controlled switch in the protection circuit normally closed to permit regular energization of the solenoid, but opened upon occurrence of warp fault to prevent closure of the protection circuit. The link 22 is normally set to effect loom stoppage and is moved to non-stopping position prior to a working stroke of lever 25 only if the shuttle is running on time. While the knock-off mechanism operates at a given time in the loom cycle closely related to the normal time of closure of the shuttle switch SS, the warp stop controlled switch WS can open any time in the cycle independently of the shuttle and it will remain open until the warp fault is corrected without regard to the condition of switch SS. Except at those comparatively rare times when a warp fault occurs when switch SS is closed the protection circuit will be open or dead when switch WS opens and there will be no sparking at contact 42.

Having thus described the invention it will be seen that changes and modifications of the foregoing specific disclosure may be made without departing from the spirit and scope of the invention.

What is claimed as new is:

1. In stopping means for a loom operating with a shuttle, a regularly moving knock-off lever, loom stopping mechanism including a force transmitter normally in the path of the lever and effective when moved by the lever to cause the mechanism to stop the loom, a normally deenergized electro-magnetic device effective when energized to move the force transmitter out of the path of the lever, a normally open loom protection electric circuit including said device closed by the shuttle to effect energization of the device, a normally open electric warp stop circuit, and means independent of the shuttle operative upon closure of the warp stop circuit to open the protection circuit.

2. In stopping means for a loom operating with a shuttle, mechanism normally operative to stop the loom at a given time in the loom cycle, a normally deenergized electro-magnetic device effective when energized prior to said time to prevent the mechanism from stopping the loom, a normally open loom protection electric circuit closed by the shuttle to energize the device prior to said time if the shuttle is running on time, a normally open warp stop electric circuit, and means operative due to closure of the warp stop circuit to open the protection circuit independently of the shuttle to prevent energization of said device.

3. In stopping means for a loom operating with a shuttle, mechanism normally operative to stop the loom at a given time in the loom cycle, a normally deenergized electromagnetic device effective when energized prior to said time to prevent the mechanism from stopping the loom, a normally open loom protection electric circuit including said device effective when closed to energize said device, the shuttle if running on time closing the protection circuit prior to said given time, a normally open warp stop electric circuit, and means independent of the shuttle operative due to closure of the warp stop circuit to prevent closure of the protection circuit and energization of said device.

4. In stopping means for a loom operating with a shuttle, stopping mechanism normally operative to stop the loom at a given time in the loom cycle, an electro-magnetic device controlling said stopping mechanism normally deenergized but effective when energized to prevent the mechanism from stopping the loom, loom protection electric circuit means normally open and including a normally closed electric switch and a normally open shuttle operated electric switch

closed by the shuttle if the latter is running on time to cause said protection circuit means to energize the device, normally open warp stop circuit means, and means actuated upon closure of the warp stop circuit means opening the normally closed electric switch to prevent energization of the device even though the shuttle closes said normally open shuttle operated switch.

5. In stopping means for a loom operating with a shuttle, a regularly moving actuator, stopping mechanism for the loom including a force transmitting element normally in the path of the actuator to be moved by the latter to effect loom stoppage, an electro-magnetic device controlling the element effective when energized to move the element out of operative relation with respect to the actuator to prevent the latter from stopping the loom, normally open loom protection electric circuit means including a normally closed electric switch and closed by the shuttle to energize said device, and normally open warp stop electric circuit means effective upon closure to open said normally closed electric switch to prevent energization of the device.

6. In stopping means for a loom operating with a shuttle, a regularly moving actuator, loom stopping mechanism including a force transmitting element normally in the path of the actuator effective when moved by the latter to stop the loom, a normally deenergized electro-magnetic device controlling the element effective when energized to move the latter out of the path of the actuator, a normally open electric switch closed by the shuttle, a normally closed switch, series electric protection circuit means including said switches and device effective when the normally open switch is closed by the shuttle to move the element out of the path of the actuator, and warp stop electric circuit means controlling the normally closed switch and effective when energized to open the latter switch to prevent energization of said device when the shuttle closes the normally open switch.
